OPEN BARREL ALUMINUM CABLE CONNECTOR

Timothy Allen Lemke, Mechanicsburg, Pa., assignor to
AMP Incorporated, Harrisburg, Pa.

Filed Sept. 14, 1973, Ser. No. 397,542

Term of patent 14 years

Int. Cl. D13—03

U.S. Cl. D26—1 A

FIG. 1 is a perspective view of an open barrel aluminum cable connector showing my new design.

FIG. 2 is a side elevational view thereof.

FIG. 3 is a top plan view thereof.

FIG. 4 is a front elevational view thereof.

FIG. 5 is a rear elevational view thereof.

I claim:

The ornamental design for an open barrel aluminum cable connector, as shown.
